UNITED STATES PATENT OFFICE.

WILLIAM L. MERSFELDER, OF DETROIT, MICHIGAN.

FURNACE.

1,416,111.

Specification of Letters Patent. Patented May 16, 1922.

Application filed October 15, 1921. Serial No. 508,042.

To all whom it may concern:

Be it known that I, WILLIAM L. MERSFELDER, a citizen of the United States, and residing at Detroit, in the county of Wayne 5 and State of Michigan, have invented a new and Improved Furnace, of which the following is a specification.

This invention relates to the construction of the upper parts of furnaces of the hot-air type, and its object is to provide a top or radiator for such furnaces which is so formed that the hot products of combustion in ascending from the fire will be caused to pass closely in contact with the upper portion 10 of this radiator, and in which the deflector which causes such movement of the furnace gases can be tipped up to rid it of the ashes which may lodge thereon.

This invention consists, in combination 20 with a radiator constituting the top of a furnace, of a deflector mounted therein to cause the products of combustion to sweep up against the top of this radiator on their way to the smoke pipe, the lower side of the 25 deflector being concave and inclining upwardly toward that side of the radiator opposite the smoke pipe, the deflector being pivoted in the upper part of the furnace.

It also consists in a pair of wing walls 30 extending from the inner surface of the radiator to the deflector at each side of the outer or bell portion of the inclined surface thereof for the purpose of preventing lateral escape of the hot gases.

It further consists in the details of construction illustrated in the accompanying drawings and particularly pointed out in the claims.

In the accompanying drawings, Fig. 1 is 40 a central vertical section of a hot-air furnace and the shell therefor. Fig. 2 is a plan of the deflector. Fig. 3 is an elevation thereof taken from the left in Figs. 1 and 2.

Similar reference characters refer to like 45 parts throughout the several views.

The shell 1, the ash chamber 2, the fire pot 3, the grate 4 and the body 5 of the furnace shown in section in Fig. 1 are of well known construction and operation, the 50 fuel being burned on the grate and the hot products of combustion passing upward and out through the smoke pipe 6. For the purpose of this description, the door 11 will be considered at the front of the furnace and

the smoke pipe 6 at the back. The top 7 55 of the furnace is usually called the radiator because of its action, and I have found that when the hot gases and flame are caused to sweep along against its inner upper surface on the way to the smoke pipe, that the heating effect of the fuel consumed is greatly increased. This radiator is formed with an upwardly flaring lower portion 8 and upper portion 9, both joining the smoke pipe 6, and the upper portion being centrally de- 60 pressed at 10.

A deflector 12 is mounted in the furnace near the bottom of the lower portion 8, being formed with a circular portion 13 of substantially the diameter of the lower end 70 of the radiator and having a flange 14 extending around about the rear half of its outer edge and so formed that it will extend under the inwardly extending ledge 15 of the body 5, which ledge supports the radiator. The deflector is also formed with trunnions 16 adapted to rest in bearings 17 formed on the lower portion of the radiator, as indicated in Fig. 1. The front portion 75 of the deflector is the heavier so it will always keep the position shown in the drawings.

The central portion 18 of the deflector is concave on its lower side and inclines upwardly and forwardly away from the smoke 85 pipe, this inclined portion connecting at the front to the flaring bell 19. The side edges of this bell are preferably straight and parallel and are adapted when the deflector is swung down to engage the wing walls 20 90 which extend from the inner surface of the lower portion of the radiator, as indicated in Figs. 1 and 2.

A pair of lugs 22 and cross bar 23 on the lower rear side of the deflector constitute a 95 loop to be engaged by a hook or poker, which may be introduced through the opening for the fire door 11, whereby the deflector may be swung to vertical position to dump the ashes which may accumulate 100 thereon. The deflector may have holes 25 near its rear edge to permit the passage of air which often comes up the rear of the furnace, which air mixes with the gases at the rear of the radiator and causes completion of combustion.

As the distance from the center of the bell 19 to the rear edge of the deflector is less

than the inner diameter of the ledge 15 of the body of the furnace, the deflector can be readily inserted into the radiator and turned until its trunnions rest in the bearings 17.

The advantage of the depression 10 lies in the fact that this inverted dome causes the hot gases to sweep around against the rounded surface of the top of the radiator 10 and prevents them from flowing directly back from the upper edge of the bell 19. The result is a greater radiation of the heat 15 of these gases. The downwardly tapering lower portion 8 of the radiator should be of such an angle that ashes do not lodge thereon. The flare of this lower portion is desirable as it offers a baffle to the air ascending within the shell 1 and around the furnace, this air sweeping up along the outside of this tapering portion of the radiator 20 and absorbing heat therefrom.

The details of construction and the proportions of the parts may all be changed by those skilled in the furnace art without departing from the spirit of my invention 25 as set forth in the following claims.

I claim:—

1. In a furnace, a radiator constituting the upper portion thereof, a smoke pipe connecting thereto, and a conoidal deflector mounted in the radiator to partially close the lower end thereof, the lower surface of the deflector being concave and inclining longitudinally upwardly away from the 35 smoke pipe to cause hot gases to sweep against the top of the radiator.

2. In a furnace, a radiator constituting the upper portion thereof, a smoke pipe connecting thereto, and a deflector mounted in the 40 radiator to partially close the lower end thereof, the lower surface of the deflector being concave and inclining upwardly away from the smoke pipe to cause hot gases to sweep against the top of the radiator, said 45 deflector being pivotally mounted to permit the ashes thereon to be dumped.

3. In a furnace, a radiator having a rounded upper portion and a downwardly tapering lower portion, a smoke pipe connected 50 to the radiator, and a normally horizontal deflector pivotally mounted in the bottom of the radiator and closing that half which is nearer the smoke pipe and having a downwardly extending loop adapted to be en-

gaged to swing the deflector to vertical position.

4. In a furnace, a radiator having an upper portion and a downwardly tapering lower portion, a smoke pipe connected to the radiator, and a normally horizontal deflector pivotally mounted in the bottom of the radiator and closing that half which is nearest the smoke pipe, said deflector being provided with a passage adjacent the smoke pipe.

5. In a furnace, a radiator, a smoke pipe connecting thereto, a normally horizontal deflector mounted in the radiator and having a normally horizontal lower edge and its middle portion concave and inclining upwardly away from the smoke pipe and terminating 70 in a flaring bell having parallel vertical edges, and wing walls extending from the inner surface of the radiator and fitting against the vertical edges of said bell.

6. In a furnace, a radiator, a smoke pipe 75 connecting thereto, a normally horizontal deflector pivotally mounted in the radiator and having a normally horizontal lower edge and having trunnions at right angles to the line of the smoke pipe, the middle portion of 80 the deflector being concave and inclined upwardly away from the smoke pipe and at substantially right angles to the line of the trunnions and terminating in a flaring bell, and wing walls formed on the radiator extending to said bell to cause the products of combustion to pass upward and sweep along the top of the radiator on the way to the smoke pipe.

7. In a furnace, a radiator having an upper portion provided with a central depression and a downwardly tapering lower portion, a smoke pipe connected to the radiator, and a normally horizontal deflector to direct the ascending hot gases against that portion 95 of the top of the radiator farthest from the smoke pipe.

8. In a furnace, a radiator having an upper portion with a central depression, a smoke pipe connecting to the radiator, and a 100 normally horizontal deflector within the radiator to direct the ascending gases against that portion of the top of the radiator on the opposite side of said depression from the smoke pipe so as to cause said gases to sweep 105 around against the rounded portion in passing to the smoke pipe.

WILLIAM L. MERSFELDER.
